(57) **CLAIM**

I claim the ornamental design for a display screen or portion thereof with graphical user interface, as shown and described.

DESCRIPTION

FIG. 1 is a front view of a display screen or portion thereof with graphical user interface showing a first image in a sequence according to a first embodiment of my new design. FIG. 2 is a second image thereof.

FIG. 3 is an enlarged view of a circled portion 3 of FIG. 1. FIG. 4 is an enlarged view of a circled portion 4 of FIG. 2. FIG. 5 is an enlarged view of a circled portion 5 of FIG. 1; and,

FIG. 6 is an enlarged view of a circled portion 6 of FIG. 2. The appearance of the transitional image sequentially transitions between the images shown in FIGS. 1-2. The process or period in which one image transitions to another image forms no part of the claimed design.

The outermost broken lines in the figures show a display screen or portion thereof and form no part of the claimed design. All other broken lines illustrate portions of the graphical user interface and form no part of the claimed design.
